HENRICUS FROGER, OF THE HAGUE, NETHERLANDS

ELECTRICAL REMOTE CONTROL SYSTEM

Application filed February 29, 1928, Serial No. 258,010, and in the Netherlands March 8, 1927.

This invention relates to electrical remote control systems especially for use with rails, points and the like and has for its object to provide an improved system of control of this character which is simple and effective in operation and provides a high degree of security and reliability.

For the said purposes there are special requirements as to reliability and for meeting the same the invention principally comprises the combination of controlling means for operation in case of short circuiting a resistance, a light signal lighted upon the said short circuiting, means for operation in case of the line comprising the said resistance becoming currentless and another light signal lighted upon the said line becoming currentless.

The other features of the invention will be disclosed when explaining the annexed diagrammatic drawings wherein some embodiments of the invention are shown by way of examples.

Fig. 1 is a representation of a first embodiment;

Fig. 2 is a second embodiment comprising a differential relay with the two coils in parallel connection;

Fig. 3 is a third embodiment with which a relay is used as the resistance which is to be short circuited for effectuating the alarm signal;

Fig. 4 is a fourth embodiment applied to a railway for safeguarding a certain part of the same e. g. at a crossing; and

Fig. 5 is a fifth embodiment applied as in Figure 4.

In Fig. 1 the source of current 1 is connected to a relay 2, the armature 3 of which is fulcrumed at 4 and normally is held low by its own weight. Another relay 5 the armature 6 of which is fulcrumed at 7 and normally is attracted, is connected in series with the relay 2, and the circuit is closed by the wires 8 with resistance 9. If the latter is short circuited the force of the magnet 2 is so far increased that its armature is attracted causing a contact at 10 between the lines 11 and 12 forming parts of a separate circuit (not shown) for lighting the alarm signal. At

the same time the force of the magnet 5 equally is increased but this fact merely causes a stronger hold of its armature 6. Upon removal of the said short circuiting only the armature 3 is released.

If however by any reason e. g. a break of the line 8, the current ceases to flow, the relays 5 and 2 are deenergized, which causes the armature 3 to remain in its lowest position and the armature 6 to fall down, so that at 13 contact is attained between the lines 14 and 15 of a further circuit (not shown) for lighting the defect signal.

It is advisable to apply a separate source of current for the signals, even to have still at least one reserve therefor, so that under all circumstances the defect signal will be given with almost certainty, but it is possible to use one single source (1), in which case the further lines 16 are provided, the circuits for the alarm and the defect signals then being provided between the lines 12 and 17 and 15 and 17 respectively. As the defect signal is the most important part of the system, it is not urgent to have a reserve for the battery 1.

The arrangement according to Fig. 2 comprises a differential relay 2^a, the windings of which acting upon the same fixed core are connected in parallel, the relay 5 and the resistance 9 being in series with the unwinding of the relay 2^a. The last named winding acts stronger on the armature 3, than the upper winding and also is so much stronger by itself that its action, decreased by the resistances 5 and 9, is at least approximately compensated by the action of the upper counter-acting winding, so that normally the armature 3 is not attracted, attraction occurring when the equilibrium is broken either by an interruption or by a short circuiting of the resistance 9.

With the embodiment shown in Fig. 3 for signaling not a separate resistance but the relay 2 itself is to be short circuited (between 8—8), whereupon its armature 3 is released. With this arrangement both the armatures 3 and 6 normally are attracted.

For dealing with the arrangement shown in Fig. 4 it will be sufficient to explain its functioning.

The normal closed circuits of the windings of relay 2' of this arrangement are from battery 1, through the adjacent switch on the right, immediately thereafter dividing, one portion going to relay 2'' and the other portion going to winding 19' of relay 2', and thereafter again dividing, one portion going to winding 18' and from there directly back to the battery 1, the other portion going from winding 19' through relay 5', wire 8', resistance 9' and rail 8 back to the battery 1.

As to that portion of the current which goes to resistance 2'', the normal closed circuits are from the battery 1, through winding 19'', where it again divides, one portion passing through winding 18'' and from there going directly back to the battery 1, and the other portion passing from the winding 19'' through relay 5'', wire 8'', resistance 9'', and rail 8 back to battery 1.

Upon a train arriving at the insulated railpiece 20 the resistance 9' is short circuited, so that the equilibrium of the differential relay 2' is broken and its armature 3' is attracted by the action of the winding 19'. Thereby contact is made at 10' and the circuit is closed, comprising one magnet 33 of a lever switch and the transformer 27 through the intermedium of which a low tension current is obtained from the high tension alternative current lines 28, 29. The said energizing of the magnet 33 causes an anticlockwise rotation of the lever armature 35, so that a contact is attained at 36, whereby a further circuit is closed comprising the stoplamps 37, i. e. the alarm signal, the line 34 and the transformer 27. As soon as the short circuiting of the resistance 9' is finished, i. e. when the train has passed the rail piece 20, the armature 3' by its own weight or by a spring (not shown) is restored to its drawn position of rest due to the fact that the magnetic action of the winding 19' almost wholly is compensated by the action of the winding 18', which is coiled in opposite direction. This winding 18' being in parallel with the resistances 9' and 5', its number of coils is greater than that of the coils of the winding 19'.

When the train arrives at the insulated railpiece 21 the resistance 9'' is short circuited, which in cooperation with the differential relay 2'' causes in a similar way as already described for the relay 2' the energizing of the other magnet 32, so that the lever 35 is turned clockwise and thereby is returned to its drawn position, with which there is no contact at 36, so that the stoplights 37 are extinguished.

If by some reason the current ceases to flow through the line 8' e. g. by a break of the resistance 9', the armature 6' of the relay 5' is released, so that a contact is made at 13' and thereby a circuit is closed comprising the

defect lamps 40, lamps 40', 41 and 43 in parallel connection with lamps 40 and the transformer 27. At the same time the equilibrium of the relay 2' is broken, so that the alarm signal also is given.

If the line 8'' becomes currentless the armature 6'' of the relay 5'' is released, whereby another circuit is closed at 13'', equally comprising the defect lamps 40, lamps 40', 41 and 43 in parallel connection with lamps 40 and the transformer 27. At the same time the armature 3'' is attracted, energizing magnet 32 to move the lever 35 clockwise to break the contact at 36 to extinguish the lights 37 in case the defect occurs in line 8'' before the lever 35 has been returned to its normal position. However it is desirable to have the defect signalized in the same way under all circumstances, for which purpose lamps 43 are provided in parallel connection with the defect lamps 40. The lamps 43 are thus so situated, that they give the same alarm sign as the lamps 37.

If the battery 1 is sufficiently put out of action both the armatures 6' and 6'' are released, but the contacts at 10' and 10'' are not closed, so that when the lever 35 at that moment happens to be in its drawn position no stop alarm would be given if the lamps 43 were not provided. It will be appreciated that under these circumstances it is not urgent to increase the safety of the system by applying a reserve for the battery 1. To the contrary it is of utmost importance that the lighting of the defect lamps and to a less degree the lighting of the stop lamps, under all circumstances is secured with almost certainty. For this purpose the relays 5' and 5'' may be duplicated at other points in their respective circuits, so that the circuit comprising the defect lamps also is closed in case one of the armatures 6' or 6'' would refuse to fall down e. g. due to its adhering by rust to the core. Still more important is the applying of reserve lamps 40' connected in parallel with the lamps 40, so that the defect signal is given even if one of the lamps 40 is burned through. Of course reserve lamps may be applied in the same way (not shown) for the stoplamps 37 and 43. It is equally important to have a reserve source of current in case the lines 28 and 29 become currentless. For this purpose a reserve battery 31 and a relay 30 are applied. Upon the current ceasing to flow through the relay 30 its armature is released and the battery 31 automatically is put in action.

If desired simple means may be applied for giving the defect information to the engineer e. g. in case the system is applied to a crossing. These means only comprises lamps 41 connected parallel to the defect lamps 40 and situated say a mile from the

crossing in the direction, from which the trains approach. The engineer, thus warned of the defect should exercise caution in approaching the crossing and should see that 5 information as to the fact of the defect is sent from the next station that he passes to the proper authorities of the railroad. At the crossing a switch 42 may be provided, which is accessible to the public e. g. after 10 breaking a glass window, so that if necessary the warning signal 41 easily may be given.

If the system is destined for functioning with trains coming from one or both 15 the sides additional insulated railpieces 44 and 46 are applied with resistances 9^a and 9^b respectively. The pieces 20 and 46 for starting the alarm signal then are placed between the pieces 44 and 21 for finishing the 20 alarm signal. Though possible, it is not necessary to apply four differential relays under these circumstances as the line 45 simply may be connected to the line 8'' and the line 47 to the line 8', provided the magnitude of the resistances in question and the 25 magnetic powers of the windings 18'-19' and 18''-19'' are so chosen that the desired equilibrium for the relays 2' and 2'' is attained.

30 The system shown in Figure 5 only differs from that of Fig. 4 in that the alarm- and defect relays are combined in single nondifferential relays 50' and 50''; further, that the lever armature switch 35 is replaced by 35 a wheel switch 54 and finally that some parts such as the reserve lamps are not shown. Such wheel switches 54 as conventionally indicated are well known in the art and comprise a rotary wheel per se having its body and alternate segments of electric conducting material, and its remaining segments of electric insulating material, so that the insulating and conducting segments alternate, said wheel with its alternating segments having 40 a smooth peripheral face, and electromagnetic means controlled by the various circuits and energized in conformity with the conditions thereof are provided with pawl and ratchet means for turning said wheel per se successively step by step a predetermined degree, 45 degrees in the form shown, at each actuation to either open or close contact at such point as may be required. The details 45 of this feature or wheel switch are old and well known to those skilled in the art and so are not shown nor claimed herein.

The strengths of the springs 52' and 53' are such, that under normal conditions only the armature 6' is attracted by the core 51', 60 which here is T-shaped.

The magnetic means for turning the wheel 54 are diagrammatically indicated at 55 as at 65 the line terminals which are to be connected at the say uneven switchings of the wheel 54, these particulars already being

known in the art. Apart from the simplification attained by the combination of the said two relays, the provision of a wheel switch or the like has the advantage, that the system with only two insulated rail pieces 70 20 and 21 is ready for use with trains arriving from both directions.

With the arrangement shown in Fig. 5 even the relay 50'' may be dispensed with in which case it is advisable to have the resistances 9' and 9'' connected in series. If the relay 50'' is dispensed with and the resistances 9' and 9'' connected in series, the left side of the battery 1 will not be connected to 8 but will be connected to say 8', the circuit 75 in such case then being from 1 to the single relay to 8'', 9'', 8, 9', 8' and so back to battery 1, thus avoiding the direct connection between battery 1 and rail 8.

The advantages of the systems disclosed, 80 which all show the principal feature of the invention mentioned above are the following.

Mechanical means which always are more liable to defects and for which reserves cannot easily be provided are avoided as far as 85 possible.

A defect is automatically signalized.

Sufficient security may be attained with comparatively simple systems, whilst equally with simple means such as a reserve battery, 90 reserve lamps, etc. the safety may be increased at will.

The possibility is given to have a stop signal easily actuated simultaneously with the defect signal and to have a very low consumption of current under normal conditions in case for the signals a separate source of current is applied.

The sensibility of the relays may be easily varied as desired.

All important parts easily may be packed up e. g. in a metal casing, so that they are inaccessible to the public.

The rail resistances may be reduced to 10 ohms.

It will need no explanation that the systems disclosed without any essential alteration may be used for other purposes such as for signaling a certain position of a point in a railway, the reaching of a certain water-level in a tank or in a water-gauge glass etc.

Having fully described my invention, what I claim is:

1. In a remote control electrical system for signaling trains at crossings, the combination of a normally open signal circuit embracing means for causing a light signal, a source of electrical energy and a movable relay part for closing said circuit, and a normally closed signal controlling circuit embracing a source of electrical energy, a resistance arranged between an insulated portion of one rail of the railroad track and the other rail of said track and a signal relay comprising said movable part and adapted to cause said part 120 125 130

to close the signal circuit upon short-circuiting of said resistance, with a normally open defect circuit embracing means for causing another light signal for indicating a defect, a source of electrical energy and a movable part of a defect relay which is so embraced by the signal-controlling circuit that its movable part is caused to close the defect circuit upon the part of the controlling circuit comprising the said resistance becoming currentless.

2. A remote control electrical system as defined in claim 1 wherein the signal relay is a differential relay.

1832 In testimony whereof I have signed my name to this specification.

HENRICUS FROGER.
